WORK HOLDER ATTACHMENT FOR
SEWING MACHINESRichard E. Tice, Dallas, Tex., assignor to Texas
Machine Attachment Company, a corporation
of Texas

Application November 8, 1951, Serial No. 255,467

10 Claims. (Cl. 112—2)

1

This invention appertains to improvements in attachments for sewing machines and especially relates to an improved work holder or table for sewing machines.

The primary object of this invention is to insure that a stitched design is formed on garments or other articles in a similar and proper manner, so that each garment or article has a stitched pattern or design which is similar in all aspects. Thus, it is the primary purpose of this invention to eliminate the possibility of human error and inadvertence on the part of a sewing machine operator engaged in stitching pockets on garments, forming special designs on garments or other articles or ancillary sewing operations and incidentally to reduce production costs and enable an increase in the rate of production to be realized.

Many articles of apparel, such as jeans, aprons or the like and various other articles made from textile materials are decorated with designs stitched therein. In present practice, it is necessary to expend considerable time and expense inculcating inexperienced sewing machine operators to move a work piece, such as a garment or other article, in the correct path of movement beneath the reciprocating instrumentalities of the sewing machine, so that the design is properly stitched on the work piece. The work piece must be manually turned and controlled so that the proper portion thereof is correctly located for penetration by the sewing instrumentalities.

For example, in forming a horseshoe design on a pair of jeans, as illustrated in Figure 7 of the accompanying drawings, it is necessary to employ at least three operators to form the design on a single garment. And the similarity of the design on a number of garments depends upon the skill of the operators.

In forming the design, one of the operators initially traces the design on the garment. This is conventionally done by sprinkling a powdery substance over a plate, which is laid on the portion of the garment to be designed and it is formed with a cutout portion of horseshoe shape. The next operator positions the garment on the work table of a sewing machine beneath the sewing instrumentalities and manually moves the garment, being guided by the outline of the design on the garment. Considerable skill and experience are required in carrying out this operation, since it is necessary for the completeness and quality of the design that a certain spacing of the stitching and a certain number of stitches per inch be provided. Therefore, the garment

2

must be moved at the proper time with the exercise of considerable dexterity and care so that it is properly positioned beneath the sewing instrumentalities. In the last step in the process of forming the exemplary horseshoe design, the third operator uses a bar tacking machine and bar tacks the open end of the horseshoe design.

It can thus be realized that the process of forming a design on garments or other articles entails the services of several operators, who must be specially trained for their particular task in the operation and who must possess a considerable degree of skill and speed.

With the instant invention, one operator can perform the entire operation, which does not depend upon the skill or speed of the operator but which is automatic and therefore insures uniformity of any particular design on the articles. The purpose of this invention, therefore, is to provide an automatically movable work holder or table, which ascribes a predetermined movement beneath the sewing instrumentalities in accordance and conformance with the outlines of a particular design. The initial tracing of a design on the work piece, the manual moving of the work piece and the subsequent bar tacking are eliminated. An inexperienced operator can turn out designed garments without any possibility of error in the design and with a considerable reduction in time and production costs.

A further object of this invention is to provide a simply constructed, compact and easily movable work holder, which can be attached to a conventional sewing machine, without necessitating modification of the sewing machine, and which can be driven by a direct drive from the conventional gear box on the head of the sewing machine.

Another object of this invention is to provide operating elements which simultaneously reciprocate in rectilinear paths of movement and at right angles to each other, the work holder being supported by the elements in such a manner that it is moved by the compound movement of the operating elements.

A further object of this invention is to provide cams for moving the operating elements, the cams being designed and formed with cam tracks in accordance with the desired path of movement of the work beneath the stationary sewing instrumentalities dependent upon the outline of a particular design.

A still further object of this invention is to provide a means for moving a work holder, so that the path of movement of the work holder

3

is identical with the contour and outline of a particular design.

These and ancillary objects and structural features of merit are attained by this invention, the preferred embodiment of which is set forth in the following description and illustrated in the accompanying drawings, wherein:

Figure 1 is a front elevational view of a conventional sewing machine to which is attached an automatically movable work holder, constructed in accordance with this invention;

Figure 2 is a perspective view of the work holder or attachment per se;

Figure 3 is a top plan view of the operating mechanism for the work holder;

Figure 4 is a longitudinal vertical sectional view taken on line 4—4 of Figure 3;

Figure 5 is an enlarged top plan view of the operating mechanism for the work holder, with parts of the operating elements shown in section to illustrate the guide means thereof;

Figure 6 is a transverse sectional view taken on line 6—6 of Figure 3;

Figure 7 is a fragmentary enlarged top plan view of the work holder, with a garment clamped thereon and depicting the exemplary design stitched therein;

Figure 8 is a top plan view of one of the cams, which actuates one of the operating elements and illustrating the cam track formed therein especially to produce the horseshoe design;

Figure 9 is a bottom plan view of the companion cam, and,

Figure 10 is a perspective view of the operating elements or slide members.

Referring now more particularly to the accompanying drawings, and initially to Figures 1 and 2, the reference numeral 19 generally designates a work holder, which includes a flat plate 12. The plate 12 is adapted to movably overlie the work table 14 of a conventional sewing machine 16. The plate is formed with a circular cut out portion or opening 18, which is adapted to underlie the reciprocating sewing instrumentalities 20 of the machine and over which a work piece is placed. The work piece is clamped or held in position over the opening 18 by a ring or hoop 22, which possesses an internal diameter substantially equal to the diameter of the opening 18. The hoop 22 is carried at the inner end of an arm 24, which is offset from the hoop and which is provided with laterally extending journals 26, the journals being journaled in upstanding spaced bearing blocks 28, which are mounted on the plate 12 at the beveled edge thereof.

The hoop 22 is spring urged into clamping engagement with the plate 12 so as to securely retain a work piece, with the portion of the work piece to be worked on overlying the opening 18. A coil spring 30 is therefore provided and is vertically disposed between the outer end of the arm 24 and the outer end of the arm 32, the outer end of the arm being offset from the inner end and underlying the arm 24. The spring 30 has its upper end encircled about a lug 34, which depends from the underside of the arm 24 to anchor the spring on the arm 24. The lower end of the spring is encircled on a bolt 36, which is threadingly disposed through the outer end of the arm 32 and which is adjustable to provide means for the convenient removal of the spring 30.

The plate 12 is supported by upstanding supporting blocks 38 and 40 which are secured at their upper ends to the underside of the plate 12.

4

at its opposing side edges. A base plate 42 supports the blocks 38 and 40, with the lower ends of the blocks being fixed to the upper surface of the base plate at its opposing ends. The inner end of the arm 32 is affixed by fastening members 44 to the supporting block 38.

The hoop 22 is raised from clamping contact with the table 12 against the urging of the spring 30 to enable a work piece to be inserted and removed from between the hoop and plate 12 by a release mechanism 46. The release mechanism is preferably controlled by a foot pedal (not shown) located for convenient operation by the machine operator. The release mechanism includes a vertically disposed roller 48 which rides on the upper surface of the arm 24 above the spring 30 and which is supported in a vertical plane by a shaft 50. The shaft is journaled in an offset bearing 52 carried by a block 54. An operating rod 56 is vertically disposed through the block for moving the block in a vertical plane, the rod being moved by a horizontally disposed operating rod 58. The rod 58 is journaled in bearing 60 and is actuated by an operating linkage 62 from the foot pedal.

The operating rod 58 simultaneously controls the release of the work piece from the plate 12 and through a clutch 64 controls the drive shaft 66 for the sewing machine. Also, through a linkage 68, the operating rod effects the lifting and lowering of the sewing instrumentalities 20.

Accordingly, when the foot pedal is depressed by the machine operator, the arm 24 is moved downwardly on its journals 26 to lift the hoop 22 from contact with the plate 12 and permit the work piece to be withdrawn. Simultaneously, the sewing instrumentalities or needles 20 are lifted and the clutch is thrown in to interrupt the rotation of the operating shaft 66 for the machine.

The base support plate 42 is movably supported by a housing 70, which is T-shaped and which includes a bottom wall 72, upstanding side walls 74 and opposed end walls 76. A cover or top plate 78 is detachably mounted on the upper ends of the side and end walls and hanger rods 80 extend upwardly from the top plate and are suitably connected to the underside of the work table 14 of the machine, whereby the housing is suspended from the work table and is mounted in an out of the way position, so as not to interfere with the movements of the machine operator.

A pair of supporting bars 82 and 84 are fixedly mounted in parallelism on the bottom wall 72 of the housing 70, the bars extending longitudinally of the housing and being spaced transversely apart to slidably receive therebetween an operating element or slide plate 86. The plate 86 is flat and has a depending base portion 88, which extends along the longitudinal center line thereof and is affixed thereto by fasteners 89.

Rollers 90 are vertically mounted on the inner sides of the supporting bars 82 and 84 and are arranged in longitudinally spaced fashion on the bars. The rollers 90 engage the underside of the plate 86 at the opposing marginal side edges thereof and cooperate with horizontally disposed rollers 92 to slidably support the plate 86 in the housing. The rollers 92 are mounted on upstanding shafts 93, which are fixedly mounted in the upper edges of the supporting bars. The rollers 92 engage the opposing side edges of the plate and constrain the plate from lateral movement, the plate being slidably held by the rollers

for movement in a rectilinear path longitudinally of the housing. The vertically arranged rollers 90 space the plate out of contact with the bottom wall of the housing and slidably support the plate during its movement between the supporting bars.

A pair of parallel cross bars 94 and 96 are transversely mounted on the plate 86 adjacent the outer end thereof and are spaced apart for the slidable reception of the base plate 42 of the work holder. The base plate 42, as seen in Figure 2, is slidably disposed through elongated slots 86, which are formed in the opposing side walls 74 of the housing 70 and are in alignment.

The ends of the cross bars 94 and 96 overlie the bars 82 and 84 and are, of course, spaced above the bars, as seen in Figure 4. Seats 100 are formed in the upper edges of the cross bars, above the bars 82 and 84, and rollers 102 are mounted in the seats and horizontally arranged for engagement with the base plate 42. The opposing side edges of the base plate are formed with longitudinal grooves or tracks 104, within which the rollers 102 are slidably disposed, so that the rollers slidably support the base plate above the slide plate or operating element 86.

The slide plate 86, through the cross bars, which are securely fixed thereto, moves the base plate 42 longitudinally of the housing, as the slide element is rectilinearly reciprocated. Means is provided for simultaneously moving the base plate 42 transversely of the housing and, for this reason, the base plate is slidably supported by the rollers 102. The movement of the base plate 42, transversely of the housing, is produced by a slide plate or operating element 106, which is reciprocated in a rectilinear path of movement, transversely of the housing and at right angles to the path of movement of the slide element 86, which is reciprocated longitudinally of the housing.

The slide plate 106 is formed at its opposing side edges with longitudinally extending grooves or tracks, which are coextensive in length with the slide plate. Rollers 110 are disposed in horizontal planes and supported by a supporting plate 112, which extends transversely of the enlarged end of the housing and has its opposing ends fastened by screws 114 to ledges 116, which are formed on the inner surfaces of the opposing side wall 74. The rollers 110, as seen in Figure 4, are spaced above the upper surface of the supporting plate 112 by spacers 118 and are disposed in the grooves 108. An elongated connecting bar 120, which forms an integral part of the operating element 106 to produce the reciprocating motion of the work holder transversely of the housing, is fixed at one end to the slide plate 106 and extends laterally therefrom. The connecting bar 120, is longitudinally disposed in the housing and is provided at its outer or free end 122 with longitudinally extending tracks 124, that are formed in the opposing side edges of the bar. The tracks 124 are formed by under cutting the side edges of the bar 120 at the outer end thereof, as seen in Figure 5. Horizontally disposed rollers 126 are mounted on the upper surface of the base plate 42 by means of upstanding shafts 128, the rollers being spaced above the base plate 42 by spacers 130 concentrically disposed on the shafts. The rollers are disposed in spaced side by side relation and are engaged with the tracks 124, as seen in Figure 3.

Thus, as the slide plate 106 is reciprocated transversely of the housing, the plate being re-

strained from lateral movement by the rollers 110 and being slidably supported thereby, the bar 120, which constitutes a lateral extension of the plate 106, is moved transversely of the housing and moves the base plate 42 transversely of the housing by means of the rollers 126, which transmit the movement of the bar 120 to the base plate. The rollers and accommodating tracks 124 are provided to enable the base plate to be moved longitudinally of the housing by the slide plate 86, simultaneously with the transverse movement of the base plate.

Thus, a compound movement of the work holder 10 is produced, the work holder being simultaneously reciprocated longitudinally and transversely of the housing.

A drive shaft 132 is vertically mounted in the housing 74, at the center of the enlarged end thereof, with the lower end of the shaft being disposed in a bearing 134. The bearing 134 is attached to the bottom wall 72 of the housing and supports the shaft, which extends through the removable top wall 78 of the housing and is adapted to be attached directly to the gear box (not shown) customarily mounted on the head of the machine and drivingly connected to the operating shaft 66 therefor.

Of course, other means may be employed for actuating the shaft 132, consisting either of a drive means independent of the shaft 66 or suitable transmission means drivingly connecting the shaft 66 to the drive shaft 132.

A collar 136 is fixedly circumposed on the shaft 132 above the bearing 134 by a radial set screw 138. The collar is formed at its upper end with an annular flange 140, which seats a cam 142. The cam 142 is eccentrically mounted on the shaft 132 by means of an off-center opening 144 formed therein and is secured to the flange 140 by a screw 146. The head of the screw is disposed in the counterbore 148 of the bore 150 formed vertically through the cam, adjacent the opening 144, and the shank of the screw is received in a threaded bore 152 formed vertically in the flange. A second or top cam 154 is provided and is fixedly superimposed on the cam 142. The cam 154 is formed with a vertical opening 156 to receive the shaft 132 and is formed with a vertical opening 158 to receive a connecting screw 160. The opening 158 is elongated and counterbored as at 162 to seat the head of the screw, the screw being disposed in a threaded bore 164 formed in the upper surface of the lower or first cam 142. The opening 158 is elongated, so that the cam 154 can be adjusted relative to the cam 142, which are fixed together by the screw 160 so that they rotate in fixed relation.

The cam 142 is formed on its lower face with a cam track 164, within which a cam follower 166 is disposed, the cam follower 166 being vertically mounted on the inner end of the slide plate or operating element 86. A cam groove 168 is formed in the upper surface of the cam 154 and a cam follower 170 is engaged therewith, the cam follower 170 depending from the slide plate 106. In this respect, an elongated axially extending slot 172 is formed in the slide plate 106, so that the plate can reciprocate over the drive shaft 132 and at one end of the slot, a recess 174 is formed in the upper face or surface of the plate, the cam follower depending from the wall of the recess and being detachably mounted in the plate. Thus, the recess is provided for supporting the cam follower in a detachable manner, the upper end of the cam follower being

threadingly disposed through a threaded opening in the wall of the recess portion.

Thus, it can be seen that basically the operation involves the rotation of the drive shaft 132, which rotates the cams 142 and 154. The cam followers 166 and 170 translate the rotary movement of the cams into simultaneous reciprocation of the slide plates or operating elements 86 and 106, which move in rectilinear paths and in right angular planes, the plate 86 moving longitudinally of the housing and the plate 106 traveling transversely of the housing. The operating element 86 supports the base 48 of the work holding plate 12 by means of the rollers 102 and the operating element 106 is connected to the base by the rollers 126. The plate 12 is moved longitudinally and transversely under the reciprocating needles 20 of the sewing machine, so that the portion of the work piece that overlies the opening 18 in the plate 12 is moved in a substantially rotary movement to advance it.

Obviously, the path of movement of the work holding plate 12 and, therefore, the movement of the work piece, as it is penetrated by the needles, depends upon the design of the cam grooves and the relative relation of the cams to each other. The grooves in the cams are formed in conformance with a particular design to be stitched on the work piece.

Considering the exemplary horseshoe design, illustrated in Fig. 7, the work piece must be moved in similar U-shaped paths but in a manner so that the needles form a certain number of stitches per inch and so that the stitches are spaced apart in a predetermined manner. The outer U-shaped line of stitches 176 is concentric to and spaced radially from the inner line of stitches 178 and the end lines 180 and 182 which connect the outer ends of the stitching 176 and 178 are bar tacked. The latter lines of stitching are produced by a conventional bar tacking mechanism (not shown) which actuates the needles 20 to produce the bar tacking, as the work piece moves in a straight line. The actuating mechanism that moves the needles to bar tack the outer ends of the horseshoe design is timed with the movement of the work holding plate 12.

The stitching commences at the point A and the foot pedal of the release mechanism is released by the operator, after the work piece has been placed on the plate 12 over the opening 18. Upon release of the foot pedal, the spring 30 biases the hoop 22 into clamping engagement with the plate 12 to securely clamp the work piece over the opening 18. The operating shaft 66 is simultaneously rotated, as the clutch is thrown in, thus producing simultaneous rotation of the shaft 132. The needles 20 are lowered for penetration of the portion of the workpiece within the hoop 22 and the work holder 10 is moved.

The work holder first moves from A to B and the timed mechanism for producing the bar tacking functions to bar tack from A to B, producing the line of stitching 180. The work holder then moves in an arc from B to C, with the needles penetrating the work piece to form the inner stitches 178. From C, the work holder moves in a straight line and the stitches 182 are formed, the bar tacking mechanism being in operation at this time and until the needles reach point D. The work holder is then moved in an arc from D to A and the outer line of stitching 176 is produced. When the needles return to the point A, the machine operator actuates the foot pedal to cut off power to the shaft 66, and consequently

the shaft 132 and to raise the needles 20. The thread is then cut and the work piece is removed from the plate 12.

With respect to the cam groove 164, which is circumferentially formed on the underside of the first or bottom cam 142, the starting point is located at 184. The cooperating cam follower 166 moves from 184 along the radius 186 as the line of stitching 180 is produced and along the curve 188, as the work piece moves, under the needles from B to C, the follower reaching approximately to the point 188 coincident with the needles arriving at C. The cam follower 166 moves on the radius 190, as the bar tacking 182 is produced to D, whereupon it moves along the section 192 of the cam track, as the line of stitching 176 is formed back to A. The section 194 is provided to produce a back stitching at point A slightly along the line 176.

With respect to the cam groove 168, which is circumferentially formed on the upper face or surface of the second or top cam 154 adjacent the marginal edge thereof, the starting point is at 196. The complementary cam follower 170 is positioned at this point, when the cam follower 166 is located at 184 on the cam groove 164. The cam follower 170 moves along the radius 198, as the cam follower 166 moves along the radius 186, and it moves along the French curve portion 200 of the cam groove 168 as the cam follower 166 moves along the portion 188 of the groove 186. The cam follower 170 is disposed along the radius 202 coincident with the positioning of the cam follower 166 on the radius 190 of the cam track 164 and the follower 170 follows the curve 204 in the cam groove 168, as the follower 166 follows the section 192 of the groove 164. The juncture section 206 between the curve 204 and the starting point 196 corresponds to the section 194 of the cam track 164.

The second cam overlies the first cam in a fixed but adjustable manner and the cams are held against relative movement, so that they rotate together in an integral manner with the radius 190 on the cam track 164 overlying the radius 202. To produce other designs or to stitch a pocket on a garment, different cams will be used, having different cam tracks and being mounted relative to each other in a different manner. But the slide plate, work holder and other elements will remain the same and operate in the same manner, as that disclosed herein. The cams 142 and 154 can be easily replaced with another set of cams by removing the supporting plate 112 and backing the bar 126 off the rollers 126 to remove the plate 106 with the plate 112. The top cam can then be disconnected from the bottom cam and the latter cam can then be removed from the flange 140.

Although the machine has been described as forming a so-called horseshoe design it is to be noted that the symbol of the horseshoe is the exclusive trade-mark property of the assignee, and the words "horseshoe design" are not to be understood as conveying a descriptive meaning, as the improved device has been developed for the purpose of applying the trade-mark directly to the jeans or other garments manufactured and sold by the assignee.

Thus, this invention is not limited to use only in forming the exemplary design but may be used, in the afore-described manner, to form other stitched designs and to stitch pockets or collars and the like on garments. Therefore, the invention is not limited to the exact con-

struction shown and described but numerous modifications of the principles of this invention can be developed, within the scope of the appended claims.

Having thus described this invention, what is claimed is:

1. For use with a sewing machine having sewing instrumentalities, means for movably supporting a workpiece beneath the instrumentalities comprising a work holding plate adapted to movably underlie the sewing instrumentalities, a first rectilinearly reciprocating operating element movable longitudinally in a path transversely of the axis of the plate, cross bars mounted on the operating element in longitudinally spaced fashion, a base member for said work holding plate, means slidably mounting the base member between the cross bars for forced movement by the operating element and unimpeded movement transversely of the operating element, a second reciprocating operating element movable transversely of the path of movement of the first operating element, guide means on the base member connecting the base member to the second operating element and guiding the base member longitudinally on the second operating element as the base member is moved transversely thereby.

2. In a movable work holder for use with a sewing machine in supporting a work piece beneath the reciprocating needles of a sewing machine, a base for said work holder movable axially and transversely of its axis, a first operating element, means moving said operating element longitudinally and in a path of movement transversely of the axis of the base, supports mounted transversely on the operating element, rollers on said supports slidably supporting the base between the supports whereby the base is moved transversely of its axis by the operating element and is free to move axially, a second operating element, means moving said second operating element in a path of movement paralleling the axis of the base simultaneously with the movement of the first operating element, a lateral arm on the second operating element and means on the base between which the arm is disposed connecting said second operating element to the base so that the base is entrained for forced axial movement by the second operating element and yet is free to move on the arm under the impetus of the first operating element.

3. In a movable work holder for use with a sewing machine in supporting a work piece beneath the reciprocating needles of a sewing machine, a base for said work holder, a first operating element, means moving said operating element longitudinally and in a rectilinear path of movement, supports mounted transversely on the operating element, means slidably mounting the base between the supports whereby the base is movable with the operating element and simultaneously free to move transversely thereof, a second operating element, means moving said second operating element in a rectilinear path transversely of and simultaneously with the movement of the first operating element and means connecting said second operating element to the base, said last means including a bar extending laterally from the second operating element and overlying the first operating element in parallelism therewith, rollers on the upper surface of the base and spaced apart to receive the free end of said bar and grooves formed in the

opposing side edges of the free end of the bar engaging the rollers.

4. The combination of claim 3, wherein said means for moving the first operating element and

5 said means for moving the second operating element includes a pair of superimposed cams, the bottom cam having a cam track formed on its underside, a cam follower engaged with said track and carried by the first operating element

10 and the upper cam having a cam groove formed on its upper side and a cam follower carried by the second operating element and engaged with said cam groove.

5. The combination of claim 4, wherein said 15 cams are fixed on a drive shaft, said second operating element overlying the upper cam and having an elongated axial slot receiving the drive shaft.

6. The combination of claim 5, wherein a 20 housing is provided for said operating elements and cams, said first operating element moving longitudinally of the housing and said second operating element moving transversely of the housing, means mounting said operating elements in the

25 housing, said housing having opposed side walls formed with elongated aligned slots receiving the base and means exteriorly of the housing connecting the base to said work holder.

7. In a movable work holder for use with a 30 sewing machine in supporting a work piece beneath the reciprocating needles of a sewing machine, a base plate for said holder simultaneously reciprocable axially and transversely of its axis, a first operating element reciprocable transversely of the axis of the base plate, means carried by said first operating element supporting the base plate and attached thereto and operatively connected to said base plate

35 in a manner so that the first operating element and base plate are unitary for movement transversely of the axis of the base plate and the base plate is free to move axially, a second operating element reciprocable in a path paralleling the axial movement of the base plate, and means

40 carried by the second operating element and operatively connected to said base plate for translating the reciprocable movement thereof into axial reciprocation of the base plate.

8. The combination of claim 7, wherein said 45 means carried by the first operating element includes companion rollers spaced apart the width of the base plate and engaging in grooves in the side edges of the base plate.

9. The combination of claim 7, wherein said 50 last named means includes a bar extending laterally from the second operating element, rollers on the base plate extending above the upper surface thereof and between which the bar is positioned permitting the base plate to be moved

60 by the first operating element in its path of movement transversely of its axis.

10. In a movable work holder for use with a 65 sewing machine in supporting a work piece beneath the reciprocating needles of a sewing machine, a base plate for said holder simultaneously reciprocable axially and transversely of its axis,

a first operating element reciprocable transversely of the axis of the base plate, means carried by said first operating element supporting the base plate and attached thereto and operatively connected to said base plate in a manner so that the first operating element and base plate are unitary for movement transversely of the axis of the base plate and the base plate is free to move axially, a

70 second operating element reciprocable in a path 75

11

paralleling the axial movement of the base plate, and means carried by the second operating element and operatively connected to said base plate for translating the reciprocable movement thereof into axial reciprocation of the base plate; a 5 drive shaft, adjustable superimposed cams secured on the shaft, cam followers carried by the operating elements engaging said cams.
